UNITED STATES PATENT OFFICE

111,584

DESIGN FOR AN ADVERTISING SIGN

John Kay, La Porte, Ind.

Application April 29, 1938, Serial No. 76,848

Term of patent 7 years

To all whom it may concern:

Be it known that I, John Kay, a citizen of the United States and a resident of La Porte, county of La Porte, and State of Indiana, have invented a new, original, and ornamental Design for Advertising Signs, of which the following is a specification, reference being had to the accompanying drawing, forming a part thereof.

In the drawing:

I claim:

The ornamental design for an advertising sign, substantially as shown.

JOHN KAY.
